UNITED STATES PATENT OFFICE.

LOUIS BEESE, OF WEST SUPERIOR, WISCONSIN.

GRAIN-DOOR FOR CARS.

SPECIFICATION forming part of Letters Patent No. 688,822, dated December 17, 1901.

Application filed June 14, 1901. Serial No. 64,565. (No model.)

To all whom it may concern:

Be it known that I, LOUIS BEESE, a citizen of the United States, residing at West Superior, in the county of Douglas and State of 5 Wisconsin, have invented a new and useful Grain-Door for Cars, of which the following is a specification.

This invention relates to supplemental doors employed in cars used for grain and 10 similar products to fit closely inside of and supplement the ordinary car-door and adapted to be folded up and suspended from the roof inside the car when not in use or when the car is being employed for other purposes than 15 hauling grain.

The invention consists in certain novel features and combinations, as hereinafter shown and described, and specifically pointed out in the claims.

20 In the drawings illustrative of the invention, Figure 1 is a side elevation, foreshortened, of a portion of the side of a car, including the doorway-opening, with one of my improved grain-doors arranged therein. Fig. 25 2 is a vertical section on the line 2 2 of Fig.

1. Fig. 3 is a longitudinal sectional elevation of the car, illustrating the construction of the inner side of the grain-door. Fig. 4 is a transverse section on the line 4 4 of Fig. 3. 30 Fig. 5 is a sectional plan view of the device on the line 5 5 of Fig. 1, and Fig. 6 is a similar view on the line 6 6 of Fig. 1.

This improved grain-door may be arranged in connection with any form of car, and in 35 the drawings 5 represents a section of the side of a car; 6, the sill; 7, the floor; 8, the cap or lintel timber, and 9 and 10 the jambs or side posts of the doorway of the ordinary construction.

40 11 is the grain-door, which fits between the jambs or side posts 9 and 10 and rests when in use by its lower edge upon the sill 6 and floor 7.

12 12 are two suspension-bars connected by 45 hinged joints 14 15 to the head timber 8 and with their lower ends attached to the rear or inner side of the door 11 by keepers 16, 17, 18, and 19, fast to the door, so that the door is vertically slidable upon the bars.

50 The lower extremities of the bars 12 and 13 are turned outward, as at 20 and 21, to prevent the door from slipping off from the bars,

as well as to form lugs with which catches 22 23 engage when the door is elevated, as illustrated by dotted lines in Fig. 3. By this simple means when the door is moved upward upon the bars 12 12 the lugs 20 21 will be in position to be engaged by the catches 22 23, which will thus support the door in its elevated position on the bars and enable it to be folded up into the top of the car and be fastened in that position by any suitable means in the ordinary manner of doors of this class.

24 25 are small clips attached to the inner 65 lower sides of the side posts 9 10 to assist in supporting the door 11 and to form guides to prevent the lower side from moving inward when being placed in position.

Attached centrally to the outer side of the 70 door 11 are two disks or plates 26 27, both centrally pivoted upon the door by a bolt 28.

29 is an arm passing in a substantially vertical line across the outer disk 27 and attached rigidly thereto by bolts or rivets 30 31, 75 the central bolt 28 also passing through this arm.

The lower end of the arm 29 extends to a point far enough downward to be within reach of a person from the ground, so that the arm, 80 which is the operative lever, may be actuated from the ground by its handle 28^a.

The upper end of the arm 29 extends upward above the disks and is provided with a hinged hasp 32, adapted to engage a staple 33 85 on the door, so that a lock 34 may be applied thereto.

35 36 are two vertical plates, one on each side of the outer face of the door near the vertical edges and secured to the door by bolts 90 37, fitting through slots 38 in the plates, so that the plates will have considerable horizontal movement. This horizontal movement of the plates 35 36 will be sufficient to permit the outer edges of the plates to project some 95 distance beyond the edges of the door and enter vertical recesses 39 in the posts 9 10 when the plates are distended, as shown more clearly in Figs. 4 and 5. These plates thus close the gap which would otherwise occur 100 between the door and the posts 9 10 and form grain-tight joints between the door and its jambs or side timbers.

Reinforcing or guard strips 40 will be ar-

ranged in the recesses 39 and upon the inner face of the side posts, as shown in Fig. 5, to form wear-plates for the plates 35 36 to prevent wear upon the wooden side timbers.

5 41 42 are U-shaped bars connected by their ends at 43 44 to the plates 35 36 and also pivotally secured at 45 46 between the plates 26 27, as shown, the bars being held in place by keepers 47 48.

10 The ends 43 44 of the bars 41 42 project beyond the edges of the plates 35 36, as shown, and are wedge-shaped or inclined on the outer faces, so that when the arm 29, together with its attached disks 26 27, are moved to throw

15 the bars 41 42 and their attached plates 35 36 to their outward positions the projecting wedge-shaped ends will fit into inclined cavities 45' 46', made for them in the bottoms of the recesses 39, so that the plates 35 36 will be

20 forced against the inner edges of the recesses and form a close-fitting and grain-tight joint between the door and the jambs. The projecting ends of the bars serve other very important purposes—viz., they receive and bear

25 the strain exerted upon the door and largely relieve the plates 35 36 from strains, leaving them free to perform their legitimate function of keeping the gap between the vertical edges of the door and the jambs closed and

30 also serving as reinforcing-strips to the plates to support them from the outside and relieving the bolts from end-thrust strains. These are important advantages and add materially to the efficiency of the door. This construction also effectually prevents any tendency

35 of the plates 35 36 to bind in the recess.

47 is a bar pivoted at its upper end at 48 in the plates and passing downward through a keeper 49 on the door 11 and adapted when 40 depressed to enter a seat 50 in the sill 7, and thus serve as a support to the lower edge of the door.

It will be readily understood that when the disks 26 27 are turned by the arm 29 the lower 45 end of the bar 47 will be thrown downward into its seat 50 at the same time that the arms 41 42, with the plates 35 36, are thrown outward, as before stated. The whole action will thus be accomplished by one movement of the one

50 arm 29.

This forms a very simple and efficient grain-door perfectly adapted to the work required

and capable of being applied to any of the different makes of cars now in use.

What I claim as new is—

55 1. In a device of the class described, a doorway-opening having vertically slotted and recessed jambs, a grain-door fitting within said opening, vertical plates arranged on the outside of the door and near the vertical edges 60 of the same, guiding-bolts 37 carried by the door and adapted to slotted openings in said plate, a pair of spaced disks 26, 27, centrally pivoted on the outside of the door, U-shaped locking-bars pivoted between said disks and 65 having their outer ends rigidly secured to the plates and projecting beyond the outer edges thereof, an operating-lever 29 secured to said disk and provided at its lower end with a handle, a locking-hasp hinged to the upper 70 end of said lever and adapted for engagement with a locking-staple on the door, a vertical bar 47 pivoted between the disks and adapted to a recess in the door-sill, and a keeper for guiding said bar, substantially as specified. 75

2. In a device of the class described, a doorway-opening, suspension-bars hinged by their upper ends to the lintel of said doorway and with lateral projections on their lower ends, a grain-door, keepers upon said door and engaging said suspension-bars, whereby said door is slidably disposed upon said bars, and catches upon said door adapted to engage said projections when said door is elevated, substantially as described. 80

85 3. In a device of the class described, a doorway-opening, suspension-bars hinged at their upper ends to a support above the doorway and provided at their lower ends with lateral extensions or projections 21, a grain-door, 90 keepers secured to said grain-door and forming guides for the suspension-bars, and hinged catches 22 and 23 carried by the door and having lower foot portions adapted to engage said projections, and operating-handle portions provided at the upper ends of said catches, substantially as specified. 95

In testimony that I claim the foregoing as my own I have hereto affixed my signature in the presence of two witnesses.

LOUIS BEESE.
